PATENTED JUNE 19, 1830.

6038X

J. ESTLIN.

FURNACE FOR BURNING STONE, COAL, OR CHARCOAL.

John Estlin
Letters Patent - Dated June 19th 1830

The Schedule referred to in these Letters Patent,
and making part of the same, containing description in the
words of the said John Estlin himself, of his Improvement
in the Furnace for burning Stone coal, & Charcoal.

I know, all men by these Presents, that I, John Estlin
of the County of Philadelphia, and State of Pennsylvania, have
invented a new and useful Furnace for the burning of Stone Coal,
or Charcoal, or either, and that the following is a full and exact
description of the construction and operation of the said Furnace,
as invented by me, to wit. A, represents the Box with a bottom
to it, which may be made either of sheet iron, or cast iron, and will
at the top. B, is a draft hole in the front part of said furnace.
C, is a piece of sheet iron pipe made round, and fastened on the back part
of said furnace, where the pipe D, is attached. D, is a slide in the
front part of said furnace, to slide over the draft hole to regulate the
draft. There is a Grate in the inside of said furnace, and rests on
flanges, which is made fast to the said box inside and leaves a space
between the bottom, and the grate, marked E. F, are fire bricks
which are placed in the said box, and rest on the flanges and grate
and extends up to the top on the front, and sides, of the said box, but
not so high in the back part, so as to leave room for the draft.
G, is a piece of sheet iron pipe with an Elbow to it, which is round
and attached to the pipe marked C, at the back part of said furnace.
H, is a piece of sheet iron with a piece of common wrought iron
fastened inside of it, - one edge of the sheet iron is turned over the
back edge of the box, and the other part turns down
in the inside of the box towards the grate and is made fast; it so
turns over as far as the edge of the fire brick, which is set into the fire
and on the back side of the box, and being suspended between

to and the bricks for the draft to pass to the pipe. A. I., are then
handles one on each side of said box. It is a flapper which is made
to shift on and off. The utility of the said furnace consists in
the superiority over the common furnaces now in use, to wit, by the
application of Stone coal to the said furnace, which keeps its heat
much longer time than in the furnaces now in use, which can be
applied to cooking of all kinds with very great advantage: one quar-
ter of a peck of Stone coal put in said furnace will keep a very
good fire four hours and a half. Philadelphia, June 25th 1830.

Witnessed,

Jacob Strumbeck
Wm. Vogel

John Estlin
